US00D650939S

(12) **United States Design Patent**
Edwards, Jr. et al.

(10) **Patent No.:** **US D650,939 S**
(45) **Date of Patent:** **** Dec. 20, 2011**

(54) **HOUSING ASSEMBLY FOR A LIGHTING FIXTURE**

(75) Inventors: **Richard D. Edwards, Jr.**, Westerly, RI (US); **Stanley A. Katz**, Westerly, RI (US)

(73) Assignee: **GreenDot Technologies, LLC**, Mansfield, MA (US)

(**) Term: **14 Years**

(21) Appl. No.: **29/386,951**

(22) Filed: **Mar. 7, 2011**

(51) LOC (9) Cl. **26-99**

(52) U.S. Cl. **D26/138**

(57) **CLAIM**

The ornamental design for a housing assembly for a lighting fixture, substantially as shown and described.

DESCRIPTION

FIG. 1 is a perspective view of a housing assembly for a lighting fixture, showing our new design;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof; and,

FIG. 7 is a bottom plan view thereof.

The broken lines shown in the drawings illustrate unclaimed environmental structure and form no part of the claimed design.
